UNITED STATES PATENT OFFICE.

JOHN W. D. FIFIELD, OF NORTH BROOKFIELD, MASSACHUSETTS.

MACHINE FOR THE MANUFACTURE OF CRIMPING-FORMS.

SPECIFICATION forming part of Letters Patent No. 281,856, dated July 24, 1883.

Application filed March 23, 1883. (No model.)

To all whom it may concern:

Be it known that I, JOHN W. D. FIFIELD, of North Brookfield, county of Worcester, State of Massachusetts, have invented an Improvement in Machines for the Manufacture of Crimping-Forms, of which the following description, in connection with the accompanying drawings, is a specification, like letters on the drawings representing like parts.

- 10 o The object of my invention is the production of a machine by which, at one operation, to cut wood into proper shape for crimping-forms.

Crimping-forms are now made by placing a 15 piece of wood upon a horizontal bed, through which is extended a rotary cutting-head having knives or blades the edges of which are shaped to correspond substantially with the edge of the form; but by machines such as 20 now in use the front edge of the form cannot be beveled to a point, for the vertical edge of the piece of wood employed is used to run against a collar on the shaft containing the cutter-head. Further, in the machines now 25 most generally in use, the wood for the form is presented to the cutter-head twice, first with one and then with the other side up. It has been attempted to so shape the knives that the 30 upper and lower edge of a piece of wood would be cut away at one operation, but in that case the edge of the wood, as it was obliged to be pressed against a guide-surface moving with the cutter, was not cut to an edge, and the edge of the form had to be subsequently 35 finished to necessary shape.

The machine devised by me contains a rotary cutter, a bed or frame having suitable ways to guide a main carriage, so that it may reciprocate on the said frame in the direction 40 of the length of the crimping-form, and a second or auxiliary carriage so supported therein as to be moved in a direction transverse, or nearly so, to the movement of the main carriage, whereby the foot part of the crimping-form may be so presented to the cutter-head as to enable the latter to follow the said foot from the toe to the leg. If crimping-forms of 45 different sizes are to be made on the same machine, this auxiliary carriage, which serves as the support for the crimping-form, will have

adjustably attached to it a holder for the wooden block which is to be fashioned to produce the crimping-form, and I have herein shown such holder as adapted to be adjusted to enable forms of different sizes to be made 55 on the same machine. I have provided my machine with a pattern-plate to determine the contour of the foot of the crimping-form, and, as herein shown, I have attached the said pattern to the auxiliary carriage, and to co-operate therewith I have employed a stud attached to a bracket connected with the bed of the machine and extended into the slot of the pattern; but a converse arrangement of parts 60 might be employed instead. I have herein 65 shown the auxiliary carriage as pivoted and made movable in the arc of a circle the center of which is on the main carriage; but it is obvious that the said auxiliary carriage might be moved in a direction more nearly at right 70 angles to the movement of the main carriage, the auxiliary carriage being in or under the control of suitable guides on the main carriage, without departing from my invention. I have also provided a carriage mover or pusher 75 adapted to move first one and then both of the said carriages, as will be described.

My invention consists, essentially, in a rotary cutter-head, a main and connected auxiliary carriage to support the blank to be shaped for a crimping-form, and suitable means to move the auxiliary carriage, combined with a pattern-plate to regulate the line of movement of the foot part of the blank being operated upon with relation to the cutter to correctly 85 shape the edge of the said foot part; also, in a rotary cutter, auxiliary carriage, pattern-plate, and pin or stud co-operating therewith, combined with the main carriage and with a carriage mover or pusher to operate both the 90 auxiliary and main carriages, substantially as will be described; also, in a rotary cutter and the main and auxiliary carriages made movable with relation to the said cutter and each other, combined with an adjustable holder to directly support the block to be made into a crimping-form, whereby forms of different sizes may be made on the same machine, substantially as will be described; also, in a main and auxiliary carriage and a pusher 95 100

to move them, combined with a separable nut and rotating screw-shaft to operate the pusher at the proper times, substantially as will be set forth; also, in a main carriage and an auxiliary carriage made movable thereon, and a pattern-plate, combined with a rotary cutter-head, which may be moved backward and forward on the frame of the machine, substantially as and for the purposes described.

10 Figure 1, in side elevation, represents a machine embodying my invention; Fig. 2, a right-hand end view of the same; Fig. 3, a detail of the separable nut and means to operate it; Fig. 4, a section of Fig. 1 on the dotted line $x-x$; Fig. 5, a side elevation and cross-section of a completed crimping-form, shown as adapted for crimping boot-fronts. Fig. 6 represents views of the pusher. Fig. 7 is a sectional detail on the line $y-y$, Fig. 1. Figs. 8 15 and 9 are cross-sections of crimping-forms in the conditions as heretofore left after having been acted upon by other machines employed anterior to my invention.

The stationary bed or frame-work A, of 25 suitable shape to sustain the working parts of the machine, has two sets of guideways, A' A², shaped as common in lathes. The ways A² receive a slide-plate, B, having a frame, B', provided with suitable adjustable boxes, B², 30 to receive the rotary shaft B³, provided with a belt-pulley, B⁴, and with a double cutter-head, C C', each having two or more cutters or blades, C³, held in slots or throats therein in an adjustable manner by screws C⁴, the inner and cutting edges of the said blades being shaped to correspond with the bevel 2 it is desired that the acting or front edge of the crimping-form shall have, as in the section Fig. 5. The slide-plate B and the rotary cutter-head C C', carried by it, are made adjustable on the frame A through a bolt, B⁵, which enables the said cutter-head to be placed in proper position to operate upon a crimping-form of any desired size. The ways A' receive, in 45 usual manner, a carriage, D, denominated the "main carriage," which, in accordance with my invention, supports an auxiliary carriage, E, herein shown as mounted on a pivot or center stud, E', in an arm of the main carriage, 50 the forward end of the auxiliary carriage having a slotted arm, E², engaged by a bolt, E³, the head and body of the latter acting as a guide.

Secured to the lower edge of the auxiliary 55 carriage is a pattern or pattern-plate, F, provided with a cam-slot c c' c² c³, which are so shaped as to determine the outline of the respective parts b b' b² b³ of the crimping-form. A pin or stud, G, on a bracket, G², enters the 60 slot in the pattern-plate. The wooden blank H, for the production of the crimping-form M, is shown as held by screws d d, extended through ears d' of the holder L, made adjustable on the auxiliary carriage E by reason of 65 the bolts d² and the slot d³, adjustment of the holder on the said carriage adjusting the ma-

chine for crimping-forms of different sizes, the nearer the holder L to the center E' the smaller the crimping-form, and vice versa.

The frame-work A, at the rear side of the 70 carriage D, has a suitable guideway for the reception of the carriage mover or pusher N, (shown in Fig. 6, and in Fig. 1 in dotted lines,) the said pusher having at its front end an incline, e, and above it a shoulder, e', both to 75 act upon a pin or roller, e², on a pin, e³, attached to the inner side of the auxiliary carriage as the pusher is moved in the direction of the arrow 4 by the screw O, having fixed bearings 5 6 and provided with a belt-pulley, 80 O', by which to rotate it. The pusher N, at its inner side, is provided with a vertical slot to receive above and below the screw O one-half of a threaded separable nut, f f', each half being provided with a slot, f², to receive 85 one of the two pins f³ on a disk, f⁴, provided with a hand-lever or handle, f⁵, the said handle, disk, and pins constituting a nut-moving device.

The blank to be made into a crimping-form 90 is sawed to resemble in outline substantially the shape that the form is to have, and my machine will fully complete the outline and bevel the sawed edge from each side toward its center, thus making a tapered or sharp 95 edge, as shown in Fig. 5. The cutter-head, as herein shown, will commence to operate upon the block H at the point 8, the parts being substantially as in Fig. 1, with the two halves of the separable nut closed upon the 100 screw O, which is kept in continuous rotation. The rotation of the screw O immediately starts the pusher N in the direction of the arrow 4, causing the incline e to act on the roll e² and move the auxiliary carriage E in the direction 105 of the arrow 10 and toward the rotating cutter-head C C', and at the same time the slot of the pattern-plate F, co-operating with the relatively-fixed pin or stud G, will cause the auxiliary carriage, and with it the main carriage 110 D, to move horizontally for such a distance and in such time as to enable the irregular edge of the foot of the block to be presented to the cutter-head to be trimmed, the said cutters conforming to the edge of the said foot, in 115 accordance with the demands of the pattern F. As the cutter reaches the point b³, Fig. 1, and commences to cut the edge of the leg portions of the blanks, the end of the pin or stud G passes under a bridge, F², (a sectional detail 120 of which is shown at Fig. 7, near the end of the pattern-plate,) and at the same time the roll e² passes the corner 14 of the pusher and meets the shoulder or end e'. The roll having been placed, as just described, on the shelf 125 between the corner 14 and shoulder e', the pusher N, in its farther forward movement by its action on the roll e², will carry the auxiliary carriage forward longitudinally in the direction of the length of the crimping-form, 130 with the leg portion in contact with the cutter-head, and at the same time the auxiliary

carriage will draw the main carriage D with it on the ways A'. The auxiliary carriage will be provided with a suitable scale or index to designate various sizes of boots or shoes, in order to indicate the point to which the holder L will be adjusted to enable the production of a form of the desired size.

Fig. 8 shows in cross-section a blank for a crimping-form as it will be left after having been once operated upon by the cutter-head of the old style of machine hereinbefore first referred to. In the said figure it will be noticed that but one bevel, 24, has been formed, and that has not been carried to the center line, x^2 , of the blank, but that a square edge, 15, has been left where the blank rested against the gage which moved with the cutter and its shaft. When the blank, reversed or turned the other side up, is again subjected to the action of the cutter, the square corner 15 will be reduced by the bevel 17, Fig. 9; but even then it will be noticed that the bevel 17 has not been carried to the center line, x^2 , but that a square edge, 15, is yet left, which, to bring it to a proper bevel, as in Fig. 5, has to be subsequently shaved by hand.

Cutter-heads have been made to produce at one operation the edge shown at Fig. 9, but never, as I am aware, to bevel a crimping-form, as shown in Fig. 5.

It is obvious that I might use but one cutter and bevel one edge of the blank to its center line, and at another operation bevel the other edge to the said center line, or substantially so, and so avoid the final hand-shaving operation heretofore common; but it is cheaper and best to bevel both corners at the same time. When the cutter-head commences to cut the leg of the blank, if the said head should be made to travel in the direction of the length of the blank and the carriage E remain at rest, the effect would be the same, and be within the scope of my invention.

The machine is stopped, after the crimping-form is finished, by separating the nut f'.

I claim—

1. In a machine for the manufacture of crimping-forms, a rotary cutter-head, a main

carriage, and a connected auxiliary carriage to support the blank to be shaped, and suitable means to move the auxiliary carriage, combined with a pattern-plate to regulate the line of movement of the foot part of the blank being operated upon with relation to the cutter to shape the edge of the said foot part, substantially as described.

2. In a machine for the manufacture of crimping-forms, the rotary cutter, the auxiliary carriage to support the blank to be shaped, pattern-plate to regulate the line of movement of the foot part of the blank, and pin or stud co-operating therewith, combined with the main carriage and with a carriage mover or pusher, to operate both the auxiliary and main carriages, substantially as and for the purposes described.

3. In a machine for the manufacture of crimping-forms, the rotary cutter, and the main and auxiliary carriages and means to move them with relation to the said cutters and each other, combined with the adjustable holder to directly support the blank to be made into a crimping-form, whereby forms of different sizes may be made on the same machine, substantially as set forth.

4. In a machine for the manufacture of crimping-forms, the main and auxiliary carriages, and the pusher to move them, combined with a separable nut and rotating screw-shaft to operate the pusher at the proper times, substantially as set forth.

5. In a machine for the manufacture of crimping-forms, the main carriage and the auxiliary carriage, and means to move it thereon, and a pattern-plate, combined with a rotary cutter-head, and with means to move backward and forward on the frame of the machine, substantially as and for the purposes described.

In testimony whereof I have signed my name to this specification in the presence of two subscribing witnesses.

JOHN W. D. FIFIELD.
